MAKE-READY GAUGE USING SIMULATED
PRINTING PRESSURE

Frank W. Shober, Pelham, N. Y.

Application May 15, 1947, Serial No. 748,246

3 Claims. (Cl. 33—147)

1

This invention relates to improvements in measuring gages and in particular to gages adaptable for taking measurements on letter press printing members.

Deficiencies in varying degrees are encountered in printing practice by reason of the fact that the various elements of a composite letter press printing form are not consistent in "height to paper." The well-known standard of measurement for the "height to paper" or type height in the United States is .918". While printers' type, as a component in a printing form, is usually quite accurate in this respect, the thicknesses of the various blocks and mountings which are assembled with half tone plates and line cuts vary considerably, and the plates themselves are subject to errors. These deficiencies of size are compensated for by the process of makeready, which requires underlays on the form or makeready corrections in the packing of the printing cylinder. Makeready, in most cases, is performed by the printing press operator at the time that a form is locked-up for printing and consequently a great deal of the pressman's time is absorbed in this preliminary operation involving trial and error. Due to the fact that a cylinder press represents a substantial capital investment this lost time in makeready during lock-up is costly.

In order to avoid this non-productive effort by the pressman at the press, and in order to produce a more satisfactory and higher quality of printing, it is the principal object of my invention to provide a printers' gage with which mounted or unmounted cuts and plates or other printing members may be accurately measured for makeready before they are arranged as a part of a printing form. In the preferred embodiment of my invention shown herein, I adapt my improved measuring gage for use on an imposing surface, which is a standard part of the equipment of practically every printing plant, whereby an accurate and firm foundation is provided for measurements, although other suitable supporting surfaces may be used. In the operation of my improved gage, pressure may be applied to the surface of the plates during measurements to eliminate errors which result when the plates and cuts are measured for height without pressure, such as with micrometers or with other height gage apparatus.

Other objects and advantages of my invention will become apparent as the description of the physical embodiment of my invention proceeds, the invention residing in the construction and arrangements of parts as shown in the annexed

2

drawings and particularly pointed out in the appended claims.

In the drawings,

Figure 1 is a side elevation view partially in cross-section showing a type height gage according to my invention assembled on an imposing surface,

Figure 2 is a top plan view of the assembly of Figure 1,

Figure 3 is an end elevation of the assembly of Figures 1 and 2, shown partially in cross-section,

Figure 4 is a view in cross-section showing details of various parts of my type height gage taken on line 4—4 of Figure 1,

Figure 5 is a section view taken on line 5—5 of Figure 1,

Figure 6 is a view similar to that of Figure 1 showing an adjusted position of my gage assembled on an imposing surface.

Referring to the drawings, and in particular to Figures 1, 2, and 3, numeral 10 indicates a part of a rigid metal imposing surface plate which is, for convenience, placed upon a table or stand for imposing operations. Surface plates of this nature are well known in the art of printing and they are accurately machined on their top surfaces and likewise have accurately machined sides as indicated by numeral 11, including a rabbeted edge cut as at 12. Other such surfaces may be adapted for use with my invention or, if desirable, a specially constructed base and stand may be supplied having suitable strength and accuracy characteristics as may be had with the conventional style imposing surface plate.

A bifurcated bracket 13, machined to conform to the side of the imposing surface at the rabbeted edge under-cut is fastened to the edge of the table by the use of cap screws 14 with a stepped alignment surface resting on the rabbeted edge 12. Projecting above the surface elevation of plate 10 are the bracket extension portions 15, 15', each of which has high and low drilled openings 16 and 16', Figure 3, therethrough, and below the elevation of plate 10 bracket 13 forms a depending portion 17, to which are assembled the two abutment pieces 18, 18'. The two sets of drilled openings 16 and 16' and the two abutment pieces 18 and 18' of differing dimensions are used to provide high and low gaging adjustment as will be understood at a later point in the specification.

A pressure lever 20 is pivotally supported between the bifurcated bracket portions 15, 15' by the use of a knurled head removable pin 21 extending through the aligned holes 16 in bracket

13 and through a suitable bearing hole in lever 20. Pin 21 is split and spread on its left hand end, Figure 3, so that it will bind slightly when placed in the pivot hole 16 and will consequently be retained in position during measuring operations. On the right end of lever 20, Figure 1, which extends over the imposing surface 10, a pressure contact member 22, Figures 1 and 2, is provided which is integral with lever 20 and which engages the top surface of a printing plate 23 therebelow, Figure 1, mounted on a suitable base 24. On the left hand end of lever 20 projecting outwardly below the level of the imposing surface, is a manipulating handle 25 housing a coiled compression spring 26 which is interposed between a plunger 27 and a threaded adjusting screw 28. Plunger 27 projects through an aperture in handle 25 to exert pressure against the abutment piece 18, tending to rock lever 20 clockwise about pin 21 so that the pressure member 22 will forcefully contact printing plate 23.

A second bracket 30, spaced apart and to the left of bracket 13, is removably fastened to the side of imposing surface plate 10 by means of the knurled head screw 31. Alignment of bracket 30 is maintained by providing a stepped machined surface which rests on the rabbeted edge 12 of plate 10, in much the same manner as in the application of bracket 13. Bracket 30 overhangs the imposing surface plate 10 and terminates in an angularly disposed end 33 to which is fastened a dial indicator 32. Dial indicator 32 of the usual style constructed for precise measurement, is rigidly held fastened to bracket 30 by the thumb screw 34. An extension piece 35 removably fastened to indicator 32 projects downwardly to make contact with printing plate 23 during manipulation of the gage.

Referring particularly to Figures 4 and 5, pressure member 22, which contacts the printing plate, is centrally cored and has assembled therewith a fibre ring 36 suitably fastened to a metal supporting ring 37, the fibre ring providing a printing plate contact element which will not deleteriously affect the design on the surface of printing plate 23. Three short compression springs 38, seated in suitable holes 39 drilled in bosses 42, are arranged to abut metal ring 37 and are guided over pins 40 fastened to ring 37, extending upwardly through the top of the bosses. Hexagon lock nuts 41 on the upper ends of pins 40 retain the assembly in place when no pressure is being exerted against a printing plate. The combined pressure exerted by the three coil springs is greater than the resultant pressure from spring 26 in handle 25 when properly adjusted, so that the metal ring 37 is always spaced from the body of pressure member 22. However, if there is a deviation from parallelism between ring 36 and the top surface of printing plate 23, the ring will conform with this irregularity inasmuch as only one spring will be stressed to any extent and the force exerted by a single spring will be overcome by the pressure of spring 26 in handle 25. Thus, when measuring plates which are not parallel to ring 36 on pressure member 22, the fibre ring will be self-adjusting and there will be no uneven wear on the ring 36.

In the operation of my device, and before a printing plate has been inserted under the pressure member, the screw 28 in handle 25 may be adjusted so that spring 26 will exert suitable pressure. Thereafter, the operator depresses handle 25 and raises the pressure member 22 away from the surface 10, at the same time com-

pressing spring 26. A mounted printing plate or other printing member is then placed under pressure member 22. Upon releasing the pressure from handle 25, pressure member 22 will be forced downwardly against the printing member and will tend to flatten out the printing plate for a substantial area to simulate pressure under printing impression. The dial indicator is then used to take an accurate reading of the height of the upper surface of printing plate 23 above the imposing surface, the extension piece 35 projecting centrally through the rings 36 and 37 to permit a reading centrally of the area of applied pressure. Dial indicator 32 must, of course, be pre-set in a suitable manner so that the readings which are observed are of the height of the printing surface of printing plate 23 under pressure from the top surface of the imposing surface plate 10. Any number of readings may be made as at corners, along sides or across the body of the plate and the error above or below type height is marked in a convenient manner at the location of measurement so that plate leveling may be done as a separate makeready operation.

Referring now to Figure 6, and assuming now that it is desired to measure the thickness of an unmounted plate, the pivoting lever 22 may be mounted at the lower position with pin 21 inserted through holes 16' in bracket portions 15, 15' and the plunger 27 will then be positioned to exert pressure against the lower of the two abutment pieces 18'. As in the aforementioned description adjustment is made on screw 28 in handle 25 so that the desired degree of pressure is being exerted to rock arm 29 in a clockwise direction about its pivoting center. The identical measuring procedure is followed as in the case of measurements for mounted plates with the exception that an extended adaptor member 35' is provided for attachment to the dial indicator to facilitate measurements on the unmounted printing plate.

When not in use it is a simple matter to remove the dial indicator bracket 30 from surface plate 10 and thereby make the imposing surface free of this obstruction for imposing operations. Likewise, the lever 20 may be removed merely by drawing out the pin 21.

It is to be understood that this description is that of a preferred embodiment of the invention and that various changes in the size and shape of component parts may be made without departing from the invention or from the scope of the sub-joining claims.

I claim:

1. In a measuring gage, in combination, a supporting surface, a spring biased pressure exerting member arranged to extend over the supporting surface, a work-piece contacting element carried by said pressure exerting member and biased therefrom by a plurality of spring units, the individual biasing pressure of each spring unit being less than that exerted by said pressure exerting member and the combined biasing pressure of the units being more than that exerted by said pressure exerting member, a handle portion integral with said spring biased pressure exerting member for releasing the pressure exerted thereby, and means to take a measurement reading on the work-piece surface adjacent the area of applied pressure.

2. In a measuring gage, in combination, a rigid plane support, a pivoted member carried by the support, a spring biased plunger mounted on one

end of the pivoted member for exerting pressure against the support which is transmitted to a work-piece resting on the support, a work contacting element on the other end of the pivoted member and spring biased therefrom by a plurality of spring units, the individual biasing pressure exerted by the spring units being less than that transmitted to a work-piece by said spring biased plunger and the combined biasing pressure of the spring units being greater than that transmitted to a work-piece by said plunger and a handle portion on the first mentioned end of said pivoted member to release the spring pressure exerted by said plunger.

3. In a measuring gage, in combination, a horizontal work supporting surface, manually releasable spring biased means extending over the supporting surface, a work-piece contacting element carried by said extending means and spring biased therefrom by a plurality of spring units, the biasing pressure exerted by each unit being less than that being exerted by said extending means, and the combined biasing pressure of

the units being more than that exerted by said extending means, and an indicator to measure the elevation of the top surface of a work-piece resting on the supporting surface engaged by the spring pressed means adjacent the area of contact thereof.
